TYPEWRITER SUPPORT

Jalva Vale, Birmingham, Ala.

Application April 8, 1944, Serial No. 530,214

9 Claims. (Cl. 248—23)

1

This invention relates in general to typewriter supports and more particularly has reference to a device for supporting a typewriter in a position inclined to the horizontal.

Typewriters are normally used when supported upon a horizontal surface. When so supported, it is necessary for the operator to sit in an upright position in close proximity to the so supported typewriter. Obviously a typewriter so supported is not susceptible for use by a person confined to bed.

As a result of the present war, many persons are confined to bed for long periods of time and even though they do not know how to operate a typewriter, could have their morale greatly increased by typing or learning to type as a pastime.

An object of this invention is to support a typewriter in a suitable position for use by a person confined to bed.

Another object of this invention is to provide a typewriter support for mounting the typewriter in various adjustable positions over a bed.

Still another object of this invention is to provide a typewriter support adapted to be clamped to a bed table and adjustable to various positions to support the keyboard of the typewriter so as to be most accessible to the operator.

It is also an object of this invention to mount a typewriter for universal adjusted movement on a base.

With these and other objects in view, which will appear more fully hereinafter, the present invention resides in the parts and combinations shown in the drawings and described in the accompanying specification.

In order to facilitate an understanding of the present invention, reference is made to the accompanying drawings.

In the drawings:

Figure 1 is a perspective view of a typewriter support according to the present invention.

Figure 2 is a vertical sectional view of the support shown in Figure 1 of the drawings.

Figure 3 is a rear elevational view of the support shown in Figure 1 of the drawings.

Figure 4 is a plan view of the support shown in Figure 1 of the drawings.

A person confined to bed and required to lie in a supine position could not very well operate a typewriter support above him in the normal position. In accordance with the present invention, a support is provided for positioning the typewriter so that the keyboard will be readily

2

accessible for use by a person confined to bed and lying in a supine position.

In the drawings one embodiment of the present invention is illustrated by way of example. This embodiment is of the type which is adapted to be clamped on to a bed table of the cantilever type, which may be located adjacent the bed so that the table will extend transversely of the bed and over the patient. Such a table has been indicated by reference character 1 in the drawings. The embodiment shown in the drawings comprises a base 2 which is provided with clamps 3 equipped with thumb screws 4 for detachably securing the same to table 1. As illustrated, the base 2 is in the form of a flat plate, but obviously it can be constructed in other forms. Extending upwardly from the base 2 is a bolt 5, which is non-rotatably mounted in a suitable socket provided in the base 2. The bolt 5 extends upwardly through a transverse slot 6 provided in a member 7 which may be pivoted about the bolt 5 and slidable with respect to said bolt by reason of the slot 6. A thumb screw 8 is threaded onto the upper end of the bolt 5 for securing the member 7 in adjusted positions with respect to the base 2. A carrier 9 is mounted on the member 7 by means of a hinge 10 which enables the carrier to be pivoted about the horizontal axis of the pintle of the hinge 10.

In order to support the carrier 9 in various positions of adjustment of the hinge 10, a plurality of links 11 are pivoted by means of pins 12 to the member 7. Extending longitudinally of each link is a slot 13 through which extends a threaded stud 14 carried by each edge of the carrier 9. A thumb screw 15 is threaded on each of the studs 14 for clamping the links in adjusted positions with respect to the studs 14.

While in the drawings the links 11 are shown to be a length sufficient to enable the carrier 9 to be moved to a vertical position, it is of course within the concept of the present invention to have the links 11 of any length necessary to adjust the carrier 9 to any desired position.

Carrier 9 is provided with a slot 16 which extends parallel to the side edges thereof as illustrated in Figure 3 of the drawings.

A carriage 17 is slidably and pivotably mounted upon the carrier 9. As illustrated, the carriage 17 has a bolt 18 fixed therein and extending through the slot 16. This enables the carriage to be pivoted with respect to the axis of the bolt 18 and to enable the carriage to be slid in a direction parallel to the slot 16. A thumb screw 19 is threaded on the end of the bolt 18 to se-

sure the carriage in adjusted positions with respect to the carrier 9.

A typewriter indicated in the drawings by reference character 20 is adapted to be secured by means of the usual anchoring screws 21 or any similar means to the carriage 17.

With a typewriter 20 secured to the carriage 17 as illustrated in the drawings, it is obvious that when the typewriter support is clamped in position on the table 1 that the keyboard of the typewriter may be inclined to the horizontal about the pintle of the hinge 10 and secured in such adjusted position by means of the clamping thumb screws 15. The typewriter may then be adjusted pivotally and for transverse movement about the bolt 5 and secured in any desired adjusted position by the tightening of the thumb screws 8. In the event that it is necessary to adjust the position of the keyboard by movement about the axis of the bolt 18, this can be easily accomplished and the typewriter secured in such adjusted position by the tightening of the thumb screw 19. Likewise, an adjustment in the vertical direction can be effected by means of movement of the bolt 18 through the slot 16. It will be noted that substantial surface engagement is provided between the relatively movable parts of the support to assure that the parts will maintain their adjusted positions.

From the foregoing description, it will be appreciated that many adjustments of the typewriter can be made to various positions in order to best suit the comfort and convenience of the patient operator. Thus, if the patient is confined so that he is required to lie in a particular position, the typewriter keyboard can be adjusted so that it will be most accessible to him when in that position.

While the present invention is particularly adapted for use by patients while in bed, it is also susceptible for use by persons in wheel chairs or other similar devices. In this connection it may be desirable in some instances to adjust the typewriter to a position nearly horizontal. For this purpose, it will be noted that the carrier 9 is provided with an opening 22 to accommodate the thumb screw 8 and that the member 7 is provided with an opening 23 to accommodate the thumb screw 19.

The present invention will be found to be particularly useful in the rehabilitation of war casualties and will find many uses in hospitals and other similar institutions.

While a specific example of the invention has been shown in the drawings and described in the specification, it is to be understood that the present invention is not confined to the specific details of the construction shown, as the various movements which in effect result in mounting the typewriter for universal adjustment may be effected with parts and devices other than that described.

I claim:

1. A typewriter support comprising a base, a carriage, means for mounting a typewriter on said carriage, and means including pivotally and slidably interconnected elements interposed between said carriage and base for mounting said carriage on said base for universal movement with respect thereto so that the typewriter can be positioned with its keyboard at various inclinations to the horizontal.

2. An apparatus for adjustably supporting a typewriter with its keyboard in various positions relative to that of a typewriter on a horizontal

support comprising a base, a carriage, means for mounting a typewriter on said carriage, and means including a member mounted on the base for pivotal and sliding movement relative to the base, a carrier pivotally mounted on said member and mechanism for pivotally and slidably mounting said carriage on said carrier for supporting said carriage on the base for pivotal movement about a vertical axis, pivotal movement about a horizontal axis and pivotal movement about an axis inclined to said horizontal axis, and horizontal and vertical sliding movement.

3. An apparatus for adjustably supporting a typewriter with its keyboard in various positions relative to that of a typewriter on a horizontal support comprising a base, a carriage, means for mounting a typewriter on said carriage, a member mounted on the base for pivotal and sliding movement relative to the base, a carrier pivotally mounted on said member, and means for pivotally and slidably mounting said carriage on said carrier.

4. An apparatus for adjustably supporting a typewriter with its keyboard in various positions relative to that of a typewriter on a horizontal support comprising a base, a carriage, means for mounting a typewriter on said carriage, a member mounted on the base for pivotal and sliding movement relative to the base, a carrier pivotally mounted on said base, a carrier pivotally mounted on said member and means pivotally mounting the carriage on the carrier for supporting said carriage on the base for pivotal movement about a vertical axis, pivotal movement about a horizontal axis and pivotal movement about an axis perpendicular to a plane containing the feet of the typewriter, and for sliding movement in a horizontal plane and in the plane containing the feet of the typewriter, and means for detachably mounting said base on a supporting member.

5. An apparatus for adjustably supporting a typewriter with its keyboard in various positions relative to that of a typewriter on a horizontal support comprising a base, a carriage, means for mounting a typewriter on said carriage, a member mounted on said base for pivotal movement about a vertical axis and for horizontal sliding movement, means for securing the member in adjusted positions on said base, a carrier mounted on said member for pivotal movement about a horizontal pivot, means for securing the carrier in adjusted positions relative to the member, said carriage being mounted on said carrier for pivotal movement about a pivot perpendicular to a plane containing the bottom of the typewriter and for sliding movement in said plane, and means for securing the carriage and typewriter in adjusted positions on said carrier.

6. An apparatus for adjustably supporting a typewriter with its keyboard in various positions relative to that of a typewriter on a horizontal support comprising a base, a carriage, means for mounting a typewriter on said carriage, and means including pivotally interconnected elements interposed between the base and carriage and pivotally connected therewith for mounting said carriage on the base for movement about a vertical axis, movement about a horizontal axis, and movement about an axis adjustably positioned and substantially perpendicular to said horizontal axis.

7. An apparatus for adjustably supporting a typewriter with its keyboard in various positions relative to that of a typewriter on a horizontal support comprising a base, a carriage, means for mounting a typewriter on said carriage, means

including pivotally interconnected elements interposed between the base and carriage and pivotally connected therewith for mounting said carriage on the base for movement about a vertical axis, movement about a horizontal axis, movement about an axis adjustably positioned and substantially perpendicular to said horizontal axis, and means mounting said carriage on the element connected therewith for sliding movement toward and away from said horizontal axis.

8. An apparatus for supporting a typewriter for use by a bed patient comprising a carriage, means for securing a typewriter to the carriage, a base, means including pivotally interconnected elements interposed between the base and carriage and pivotally connected therewith for mounting the carriage on the base for movement about a vertical axis, movement about a horizontal axis and movement about an adjustably positioned axis substantially perpendicular to said horizontal axis.

9. An apparatus for supporting a typewriter for use by a bed patient comprising a carriage, means for securing a typewriter to the carriage, a base, means including pivotally interconnected elements interposed between the base and car-

riage and pivotally connected therewith for mounting the carriage on the base for movement about a vertical axis, movement about a horizontal axis, movement about an adjustably positioned axis substantially perpendicular to said horizontal axis, and means mounting said carriage on the element connected therewith for sliding movement toward and away from said horizontal axis.
